UNITED STATES PATENT OFFICE.

ISAAC W. LITCHFIELD, OF NEWTONVILLE, MASSACHUSETTS.

WRENCH.

Application filed May 5, 1921. Serial No. 467,182.

This invention relates to wrenches and more particularly to wrenches of the type which provide for relative adjustment of the jaw and operating member in order to facilitate engagement with the work or object.

It has been proposed to provide a wrench having a head pivoted to the wrench handle and adjustable to different angular positions. It has also been proposed to provide a wrench of this type wherein the head is pivoted to means movably connected with the wrench handle whereby adjustment between the head and handle is effected. In all devices of the types above referred to, with which I am acquainted, separate movable means are necessary to effect relative adjustment of the head and handle and to retain the head in position after the adjustment has been made. An object of this invention is to provide a wrench of this type wherein the means providing for the angular adjustment of the head to its several positions is also automatically operable to retain the head in each position of adjustment.

Furthermore, many constructions of this character heretofore proposed are seriously defective in operation in that the adjusting and retaining means do not possess sufficient strength and rigidity to stand the applied strain, which results in breaking or slipping of the adjusting and retaining means when stress is transmitted by the handle. A further object of this invention is to provide a wrench having improved adjusting and retaining means sufficiently strong and so positioned and arranged that such defective operation thereof will be prevented. A further object of the invention is to provide a ratchet adjustment preventing relative movement between the jaw and operating member when the work is moved and made effective by movement of the operating member in a direction opposite to that in which it is desired to move the work. A further object of the invention is to provide a wrench having angularly adjustable jaw and operating members and automatically operated locking and releasing connections between said members.

Stated broadly, the wrench of the present invention comprises a head or jaw member and an operating member so connected, as by the coaction of serrated slots in one of said members and elements on the other of

said members yieldably urged into engagement with the serrations of said slots, that said members are capable of relative angular adjustment and retained automatically in their several positions of adjustment.

The invention is capable of receiving a variety of mechanical expressions one of which is shown on the accompanying drawing, but it is to be expressly understood that the drawing is for purposes of illustration only and is not to be construed as a definition of the limits of the invention, reference being had to the appended claims for that purpose.

In the drawings:

Fig. 1 is a plan of a wrench embodying the present invention showing one operating position of the head and operating member;

Fig. 2 is a side view of the wrench;

Fig. 3 is a sectional view on the line 3—3 of Fig. 1;

Fig. 4 is a sectional view on the line 4—4 of Fig. 1; and

Fig. 5 is a view similar to Fig. 1 showing another operating position of the head and operating member.

Referring in detail to the drawing, wherein the same reference characters designate corresponding parts in the several figures, the embodiment shown comprises a plate-like head or jaw member 10 of any suitable material, shape and size, an operating member or handle 11 made of any suitable material, shape and size such as pressed steel pressed into the form of a channel, and yieldable means associated with the jaw and operating members, shown in the form of a leaf spring 12 one end of which is secured to the operating member and the opposite end of which bears against the head or jaw member to retain said members in their several positions of adjustment in a manner to be herein described.

The head or jaw member 10 is formed with a jaw 13 of suitable shape and size according to the general character of objects to be engaged, and with generally arcuate slots 14 and 15 which are spaced from each other in the plane of said head or jaw member, i. e. circumferentially of its imaginary axis of movement, and which are angularly disposed, i. e. the lines of general direction of said slots being disposed at an angle to each other, one or more walls of said slots being serrated or otherwise suitably formed

to provide means of engagement with elements on the operating member. In the form illustrated, the inner wall of the slot 14 and the outer wall of the slot 15 are formed with a plurality of serrations or teeth 16 and 17 respectively, and the slots are sufficiently wide to provide for lateral movement therein of pins or bolts 18 and 19, rigidly secured to the operating member, said pins or bolts extending through the slots 14 and 15 respectively and suitably aligned openings in the operating member 11 and being held against displacement by threaded engagement with nuts 20 and 21 respectively. The pins or bolts 18 and 19 are adapted to engage the serrations or teeth 16 and 17 respectively in the several adjusted positions of the head or jaw member and the operating member, the engagement being automatically made effective by the spring 12 after each adjustment of said members.

The leaf spring 12 may be mounted in any suitable way. In the form shown it is positioned to bear against relatively opposite surfaces of pins or other suitable elements 22 and 23 disposed in spaced relation and extending through the walls of the operating member 11 adjacent the open side of the channel, said pins being rigidly connected with the operating member in any suitable manner, as by riveting their free ends thereto. One end of the leaf spring 12 is provided with a stop or detent 24 which engages the pin 23 to prevent displacement of the leaf spring. Constant tension on the leaf spring 12 is maintained by its arrangement and association with the head 10 and the pins 22 and 23, while the spring and connections between the jaw and operating members provide for relatively lateral and rotary movement of said members in order to facilitate their adjustment.

The embodiment of the invention herein shown also includes a ratchet adjustment, the serrations or teeth of one or more of the slots being suitably formed for this purpose. Referring to Figs. 1 and 5, it will be noted that the serrations or teeth 16 are inclined in one direction, and, while normally preventing relative movement between the head or jaw member and the operating member when the work is being moved, the inclination of the serrations or teeth permits ready movement of the operating member relatively to the jaw member in a direction opposite to that in which the work is being moved to facilitate relative adjustment of the two members.

In the position shown in Fig. 1 the jaw 13 may be engaged with the work or object to be moved by the wrench, the pins or bolts 18 and 19 being engaged with the serrations or teeth 16 and 17 respectively. The leaf spring 12 automatically retains the jaw and operating members in their position of ad-

justment, the coacting bolts and teeth preventing relative movement between the jaw and operating members while the work is being moved. Relative movement between the head or jaw member and the operating member is effected by the thumb of the hand in which the wrench is held. For this purpose the head is provided with a peripheral knurled or otherwise suitably formed portion 25 adapted to be engaged by the thumb. The leaf spring 12 and the slot and bolt connections between the jaw and operating members provide for relative lateral and rotary movement between said members, because pressure of the thumb against the head 80 overcomes the tension of leaf spring 12 imparting a lateral movement to the head to free the teeth from the bolts whereupon a rotary movement may be imparted to the head to effect adjustment of the same. By 85 similar operations the head can be adjusted to any position within the limits of the slots 14 and 15, according to the angularity of the handle which it is desired to obtain.

When the ratchet adjustment above referred to is provided, the head or jaw member 10 and the operating member 11 are adjusted to their several positions, selectively, by movement imparted to the operating member in a direction opposite to that in which it is desired to move the work or object, the serrations or teeth 16 and 17 and the pins or bolts 18 and 19 being formed as heretofore described to provide for their disengagement and angular movement of the operating member.

My invention is susceptible to various embodiments within the scope of the following claims some of which will now readily suggest themselves to those skilled in the art, and it is to be expressly understood that the present disclosure illustrating one embodiment is not to be regarded as limiting the invention, as changes may be made in the details of construction, arrangement and proportion of parts, and certain features used without other features, without departing from the spirit of this invention. Reference is therefore to be had to the claims hereto appended for a definition of the limits of the invention.

What I claim is:—

1. A wrench comprising a jaw member, an operating member, and connections therebetween comprising a plurality of angularly disposed serrated slots in one of said members, and means on the other of said members simultaneously engaging a serration in each said slot.

2. A wrench comprising an operating member and a head member having jaws formed therein, each said member being adjustable as a unit to different angular positions, and means providing for relative adjustment of said members comprising slots 130

- formed in one member at a large angle with respect to each other and connecting means on the other member simultaneously engaging in both said slots.
5. 3. A wrench comprising an operating member and a head member having jaws formed therein, means providing for relative adjustment of said members comprising angularly related slots formed in one member and connecting means on the other member simultaneously engaging in both said slots, and means for retaining said members in position after each adjustment thereof.
10. 4. A wrench comprising a jaw member, an operating member, connections therebetween providing for relative angular adjustment of said members to several positions, said connections comprising a plurality of angularly disposed serrated slots in one of said members and means on the other of said members engaging in the serration of said slots, and yieldable means for automatically retaining said members in their positions of relative adjustment.
20. 5. A wrench comprising an operating member and a head member having jaws formed therein, and means providing for relative angular adjustment of said members comprising angularly disposed serrated slots formed in one member and connecting means on the other member engaging in the serrations of said slots.
25. 6. A wrench comprising an operating member and a jaw member, connections therebetween providing for relative angular adjustment of said jaw member and said operating member, said connections comprising a plurality of angularly disposed serrated slots in one of said members and pins on the other of said members adapted to engage the serrations of said slots, and yieldable means for retaining said pins in engagement with the serrations of said slots and providing for relative adjustment between said jaw and operating members.
35. 7. A wrench comprising an operating member and a head member having jaws formed therein, and means providing for relative movement of said members to effect relative adjustments therebetween, said means comprising a plurality of serrated slots angularly related to each other formed in one of said members and connecting means on the other of said members simultaneously engaging in the serrations of both of said slots.
40. 8. A wrench including two members connected for relative adjustment, one of said members being provided with a plurality of angularly related slots spaced from each other in the plane of said member, a wall of each slot being formed with serrations, and a plurality of elements on the other member operative to engage the respective serrations selectively.
45. 9. A wrench comprising an operating member, a member provided with jaws and having circumferentially spaced slots formed therein, and a yielding pivotal connection between said members providing for relative adjustment to different angular positions and comprising means on the operating member engaging in said slots and a spring cooperating with said members.
50. 10. A wrench comprising an operating member and a jaw member, means providing for relative angular movements of said members to effect adjustments of the same, said means comprising a plurality of slots angularly disposed with respect to each other formed in one member and connecting means on the other member simultaneously engaging in said slots, and means normally retaining said connecting means in their positions of adjustment and displaceable to provide for movement of the connecting means while said adjustments are being effected.
55. 11. A wrench comprising a jaw member and an operating member relatively adjustable to several positions, one of said members being provided with slots and teeth formed in relatively opposite walls of said slots, means on the other member engaging said teeth in the several adjusted positions of the members, and means associated with said members for retaining the same in their positions of adjustment.
60. 12. A wrench comprising a jaw member and an operating member relatively adjustable to several positions, one of said members being provided with angularly disposed slots and teeth formed in relatively opposite walls of said slots, the other member engaging the teeth of both slots in the several adjusted positions of the members.
65. 13. A wrench comprising jaw and operating members connected for relative adjustment to several positions, one of said members being provided with angularly disposed slots and teeth formed in relatively opposite walls of said slots, the other member engaging the teeth of both slots in the several adjusted positions of the members, and yieldable means associated with said members for retaining the same in their positions of adjustment.
70. 14. In a wrench, the combination of an operating member, a head provided with a jaw portion and slots, a wall of each slot being formed with inclined teeth, connecting means extending through said slots from the operating member and adapted to engage said teeth, and means for holding said connecting means in engagement with said teeth, said connecting means cooperating with said teeth to provide a ratchet adjustment.
75. 15. In a wrench, the combination of an operating member, a head provided with a jaw portion and slots, said head and the operating member being connected for relative adjustment.

ative adjustment to several positions, teeth formed in relatively opposite walls of said slots, connecting means extending through said slots from the operating member and adapted to engage said teeth, and yieldable means associated with the head and said operating member and normally urging said connecting means into engagement with said teeth.

16. A wrench comprising an angularly movable head provided with a plurality of slots circumferentially spaced with respect to the axis of said head, a wall of each slot being provided with serrations, an operating member, and connections between the head and operating member engaging the serrations of each slot.

17. A wrench comprising an angularly movable head provided with a plurality of slots circumferentially spaced with respect to the axis of said head, an operating member, connections between the head and operating member engaging in both slots and displaceable therein to provide for relative adjustment of the members, and resilient means for holding the parts in position after each adjustment of the same.

18. A wrench comprising an operating

member, a head member rotatably mounted on the operating member and having rigid jaws formed therein, and means providing for adjustment of said members to different angular positions comprising angularly related slots in one member and connecting means on the other member engaging in both slots and displaceable therein to permit rotation of said head member about an imaginary axis outside of said slots.

19. A wrench comprising an operating member and a jaw member, means connecting said members and providing for relative movement of the same to different positions of angular adjustment, said means comprising angularly disposed serrated slots in one member and a connecting device on the other member extending through said slots, and means normally retaining said connecting device engaged in the serrations at each position of adjustment of the parts, said means being operable by relative movement of said first-mentioned members to release the connecting device from engagement with said serrations.

In testimony whereof I have signed this specification.

ISAAC W. LITCHFIELD.
